UNITED STATES PATENT OFFICE

CHARLES G. HOLMES, OF MILWAUKEE, WISCONSIN

GRATE

Application filed April 20, 1925. Serial No. 24,572.

This invention relates to grates as employed in warm air furnaces, boilers and like heating plants for dwellings or other buildings, and its object is to provide a grate which is highly efficient in clearing the contents of inactive material.

5 A further object of the invention is to co-ordinate the operation of the grate and its dump section, whereby these may be simultaneously operated by the use of but one lever.

10 A still further object of the invention is to so design the grate that it may be entirely cleared of the deposits or residue usually remaining in the center of the grate after the firepot has become empty.

15 Another object of the invention is to make the same of few and simple parts, whereby the installation of the grate will be an easy matter, and removal will not entail difficulty through parts burned tight by the heat.

20 With the above objects in view, as well as others that may be suggested by the description and claims to follow, the invention consists of a novel arrangement and combination 25 of parts, and in order that the same may be better understood, reference is had to the accompanying drawings in which

25 Figure 1 is a plan view of the novel grate as installed in the base of a furnace or boiler; Fig. 2 is a section on the line 2—2 of Fig. 1, showing the application of an operating lever;

30 Fig. 3 is a frontal view of the installation as disclosed by partly breaking away the front wall of the furnace or boiler, as well as the frontal position of the grate;

35 Fig. 4 is a vertical section of the grate, disclosing a longitudinal view of the dump section;

40 Fig. 5 is a detail section, taken on the line 5—5 of Fig. 1;

Fig. 6 is a detail section, taken on the line 6—6 of Fig. 2.

45 Referring specifically to the drawings, 12 denotes the frontal portion of a typical fur-

nace or boiler at site of the grate and ashpit, and the latter is shown with a bottom 13, top 14, side walls 15 and rear wall 16. Since the invention is not directly concerned with other parts of the furnace or boiler, such parts are 50 not shown.

The novel grate comprises principally a circular structure 17 of openwork, dished to direct its contents toward the center, which is cut out in oval form, as shown at 18. As 55 grates of this form are usually operated or swung horizontally to shake their contents, the present grate is formed with three equally-distributed marginal flanges 19, which are adapted to ride on as many rollers 60 20, one of these being at the rear under the grate and the other two on opposite sides toward the front. The stub shafts 20^b of these rollers are supported by brackets 56 on the ashpit walls, and the manner in which they 65 are mounted being immaterial to the present invention.

The mechanism designed to impart the swinging motion to the grate in either direction originates with a hand lever 21, shown 70 in Fig. 2. This lever is formed with a socket 21^a to fit a tenon 22 forming the upper end of a vertical arm 23. A common, transverse bore 24 for the attachment of the hand lever to the arm by a crosspin is provided in case a permanent connection is desired between the parts involved. However, these parts may be operatively connected without any fastening device; and the hand lever is preferably made 75 separate from the arm for facility in shipping and to enable the lever to be put away or hung where not readily accessible to a child or other person in a mood to tamper with the grate.

The lower end of the arm 23 is pivoted to a 85 link 25 at 26, the opposite end of this link being connected by a loose bolt 27 to an ear 28 projecting from the front wall 12 of the furnace. The upper part of the arm is mortised 90 at 29 to receive a tenon forming the outer end

of a horizontally positioned bar 30. A loose bolt connection 31 is made at the intersection of the bar 30 with the arm 23. The bar extends through an opening in the front wall 12 toward the rear of the ashpit, and it will be seen that when the hand lever 21 is moved back and forth, a similar motion will be assumed by the bar 30.

The movement of the bar 30 is alongside the grate 17, and the grate is operated by the bar through the following connection: The inner end of the bar is made in hook form, as shown at 32, to engage a lug 33 formed in a receptacle 34 integral with and depending from one side of the grate. The receptacle is interiorly divided to permit the insertion and lowering of the bar portion to engage the lug, and the walls of the opening recede toward the ends thereof as shown at 35, to allow for the arcuate travel of the grate as against the straight course of the bar.

In order that the bar 30 may be locked to maintain the grate in normal position under ordinary conditions, it is cut with a slot 36 where it issues from the front wall 12 of the furnace to receive an impeding cam 37 from above. The cam is an extension of a plate 38 mounted on a bolt 39 on the wall 12, the latter also having limiting lugs 40 in relief for a handle 41 of the plate 38 whereby the cam 37 is swung from the locking position in which shown to a position free of the bar, and vice-versa. This locking device, when applied, not only makes it readily evident that the grate is normally positioned—a factor whose importance will appear later—but also that such normal position will not be changed should the bar 30 or its associate elements receive a jolt, shock or blow from some person or object in the vicinity of the furnace.

The dump section and its relation to the grate arrangement will now be taken up. As is apparent from Figs. 1 and 4, the dump section 42 occupies the grate opening 18 and has the form of an Indian club laid on its side, but with its upper part reduced to flat form. This reduction enables the dump section to meet and form the bottom of the dished formation of the grate, whereby the grate contents will have a tendency to close toward the center thereof. The dump section is necessarily of heavy construction to withstand heat and weight, and is cast throughout its body portion with a series of large, circular fins 42^a, whereby it will have a maximum cooling efficiency consistent with its strength. The trunnion section 43 meeting one end of the dump section is relatively long as compared with the section 43^a projecting from the other end. The grate is formed with sunken receptacles 44 to receive the trunnion sections 43 and 43^a, the dump section body having lugs 45 at its ends on the under side which are spaced to co-operate with the receptacles 44 in limiting the endwise motion or play of the

dump section. The receptacles 44 also form guides when the dump section is rotated in one or the other direction. In such event, it will be evident that the reduced or flat design of the dump section on its upper side enables such side to be considerably spaced from the contiguous side of the grate opening 18 when the dump section is swung through a quarter-turn or thereabouts by a turn of its spindle in one or the other direction. The opening created thus serves as an exit when the grate contents are to be dumped or clinkers removed.

In order that the object of efficiently shaking or clearing the grate may be fulfilled, it is desirable that the dump section be agitated simultaneously with the grate, this being accomplished through the following arrangement: Under the frontal portion of the ashpit top 14 is secured—by means soon to be made apparent—a lining plate 46 extending in transverse direction, as is clearly denoted by dotted lines in Fig. 1. The medial portion of this plate is formed on the under side with an arcuate gear rack 47, suitable to receive a bevel pinion 48 from beneath. This pinion is mounted on a frontal angular reduction 43^b of the trunnion section 43, being backed by a pair of lugs 43^c projecting from the latter, and retained by a cotter pin 43^d passed through the reduction 43^b. It will now be seen that the turning of the grate in one or the other direction will rock or twist the dump section accordingly. With the dump section calculated to turn only about 90 degrees in either direction, it will be seen that the bevel pinion 48 need not be entire in circumference; a segmental design—as shown in Fig. 3—will serve the purpose, saving material and giving greater clearance below.

A unique arrangement is provided for the retention of the dump section in its proper working position without the use of bolts or other extra parts subject to burning or corrosion from the intense heat in the firepot. To install the dump section in conformity with the retaining arrangement, it is lowered upon the grate—minus the pinion 48—toward the right according to Figs. 1, 2 and 4 so as to advance the trunnion section 43 through the frontal receptacle 44 as far as possible, the body of the dump section being, however, inverted. This movement will position the dump section slightly further to the right than shown, whereby the end of the trunnion section 43^a will clear a cross-element 49 at the rear of the grate opening 18 as dropped into the corresponding receptacle 44. The dump section may now be backed to position the end of the trunnion section 43^a under the cross-element 49, this movement placing the dump section lugs 45 in a position where they will move next inside the respective receptacles 44 as the dump section is allowed to turn back to the normal position shown. It will now be

seen—especially in Fig. 4—that the dump section is not only locked by the lugs 45 from endwise motion, but cannot rise out of place at the rear because of the overlying cross-element 49. With the pinion 48 fitted and in mesh with the overlying gear rack 47, it will be obvious that the front end of the dump section is also retained in place against any vibration or other shock incident to its operation, all without the use of any bolt or other extra part liable to damage, looseness or loss.

The lining plate 46 is also secured without the use of bolts. As viewed from the front, the right-hand end of the plate is secured 15 as more clearly shown in Figs. 1, 3 and 5. Thus, the corner inside the top 14 and right-hand side wall 15 of the ashpit is cast with a lug of inverted-T form, whereby it has lateral base sections 50 and a medial section 50^a rising 20 therefrom. The end of the plate 46 is medial- 25 slotted to give it a forked shape, as denoted by the sections 46^a. The plate positioned next under the top 14 is now advanced to seat its fork sections 46^a upon the base sections 50 of the wall lug, such sections receiving 30 between them the medial lug section 50^a. The plate is thus locked from motion in any direction except that from which applied; and the possibility of the latter motion is precluded 35 by the fastening of the plate at its left-hand end. As suggested in Figs. 1 and 2, this end of the plate is also cut with a slot 46^b to clear a lug 51 depending from the ashpit top 14 as it is swung up to the latter opposite the left-hand side wall 15. A cotter pin 52 is now passed through the lug 51 underneath the plate 46 to support the same in set position.

To prevent the hooked end of the grate-operating bar 30 from rising out of engagement with the grate-lug 33, a device associated with the lining-plate 46 and shown more clearly in Figs. 2 and 6 is employed. 40 This device comprises principally a lug 53 made near one end with a pair of outwardly directed round studs 4. The plate is adapted to be hung by these studs in two ears 55 projecting from the left-hand end—when 45 considered from the front—of the plate 46. The lug is hung in the ears before the plate 46 is set in place; and after this is done, it will be seen that the ashpit top 14 retains the lug from dislocation. As shown in Fig. 2, 50 the lug hangs transversely of the bar 30 and terminates in close proximity to the upper edge of the latter, thus serving to obstruct the rise of the bar during its operation or from vibration or shock. If the bar is, however, to be removed for any reason the lug 55 may be swung aside in the direction of the arrow in Fig. 6, the upper edge of the lug being for this reason rounded, as shown at 53^a.

60 The novel grate, aside from its obvious

simplicity, embodies a number of features which render it in many ways a distinct departure from grates of prevalent types. First, when the hand lever is operated, the entire grate is agitated, affecting the contents along the whole surface of the grate. Second, a full, clear opening can be created on either side of the dump section by using the original shaking lever. Third, both the grate and the dump section are operated by one lever, eliminating an extra task or a change by the operator from his upright position. Fourth, the dump section when placed in position automatically locks itself, making it impossible for clinkers or other foreign matter to displace it while the grate is operated. Fifth, when the dump section pinion has been secured in its place, the dump section and the grate become locked against possible displacement during shipment. Sixth, the dump section opening for removal of clinkers can always be located on the side opposite from that in which the grate is swung. And seventh, bolts and nuts are done away with at all points subject to heat, other simple expedients being employed to make the assembling or taking down of the grate an easy task.

I claim:

1. A furnace formed with a support, a grate with an internal opening seating on the support, a dump section having journals and being rockably hung in the grate and across said opening, means for reciprocating the grate in a horizontal plane about a vertical axis, and a gearing between the support and the dump section whereby the movement of the grate will induce the rocking of the dump section, said gearing comprising a pinion on one of said trunnions and a rack segment on said support and engaging said pinion.

2. A grate of dished formation and having an opening in its bottom, receptacles at opposite ends of the opening, an invertible dump section hung in the opening by trunnions seating in said receptacles, lugs depending from the trunnions adjacent to the receptacles to lock the dump section from endwise motion when in normal position, and abutments over the trunnions to lock the same from rising out of their seats when the dump section is in normal position, the dump section being capable when inverted of backing to clear one of its trunnions from its corresponding abutment, whereby to permit the dump section to be lifted out of the grate.

3. A grate structure comprising a housing, a grate supported therein and having an opening within its periphery with oppositely located receptacles, means for reciprocating the grate in a horizontal plane about a vertical axis, a rockable dump section hung in the grate across the opening and having end trunnions seating in said receptacles, a gear

carried by one of the trunnions, lugs depending from the trunnions adjacent to the receptacles to lock the dump section from endwise motion, a gear rack carried by the housing and receiving said gear in mesh from below whereby to lock the corresponding end of the dump section from rising out of its receptacle, and an abutment carried by the grate over the trunnion at the opposite end of the dump section to lock such end from rising out of its receptacle.

In testimony whereof I affix my signature.

CHARLES G. HOLMES.
